Byrnes, Robbins & Parmalee

UNITED STATES PATENT OFFICE.

FLORENCE C. BIGGERT, JR., OF PITTSBURGH, PENNSYLVANIA, ASSIGNOR TO UNITED ENGINEERING & FOUNDRY COMPANY, OF PITTSBURGH, PENNSYLVANIA, A CORPORATION OF PENNSYLVANIA.

SHEET-OPENING MECHANISM.

Original application filed September 27, 1923, Serial No. 661,406. Divided and this application filed November 4, 1926. Serial No. 146,126.

The present invention relates broadly to the art of metal working, and more particularly is applicable to the manufacture of sheets in packs and the opening of such 5 packs as required to form the individual sheets.

It is well recognized in the art that considerable difficulty is frequently experienced in the opening of packs. This work is usually 10 accomplished entirely by hand and not infrequently results in such a mutilation of the sheets that the entire sheets or substantial portions thereof are discarded. The present invention provides improved means 15 for opening the packs whereby the sheets are easily separated without mutilation thereof by tearing, wrinkling or cutting.

In the accompanying drawings there is shown, of purposes of illustration only, one 20 embodiment of the present invention, it being understood that the drawings do not define the limits of the invention, as changes in the construction and operation therein disclosed may be made without departing 25 either from the spirit of the invention or the scope of my broader claims.

In the drawings:

Figure 1 is a top plan view of the sheet 30 separating mechanism, and
Figure 2 is a view partly in elevation and partly broken away of the structure shown in Figure 1.

In carrying out the present invention there 35 may be provided a separating and stripping mechanism comprising a pair of vertical standards 2 spaced a sufficient distance to receive therebetween a pack of sheets, the standards preferably being connected by suitable brace rods 3 carried by brackets 4 fixed to the standards. In order to prevent 40 interference to the passage of the sheets through the mechanism, the rods 3 are preferably positioned slightly below the path of travel of the pack and in such manner as to 45 form a temporary support therefor.

The mechanism further comprises a pair of gripping tongs 5 having a pivotal connection 6 and adapted to grip the leading end of the sheets of the pack and draw the same 50 through the opening or separating mechanism. These gripping tongs may carry a pair of flanged rollers 7 engaging brackets 8 by means of which the tongs are guided.

The free end portions of the arms of the tongs extend at an angle and cross each other in such manner that they are adapted 55 to be engaged by link 9 carried by suitable drawing mechanism 10 having an eye 11. Any suitable power device may be connected through the eye to pull the gripping tongs along the tracks in order to draw the pack between the standards 2 and cause rods 12 inserted between the sheets and engaging against one edge of the standards to strip 60 and separate the individual sheets in the pack. The insertion of these rods may be accomplished in any desired manner by previously slightly separating the leading edges 65 of the sheets by hand or by passing the same through deep buckling levelers as disclosed, for example, in my copending application Serial No. 661,406, filed Sept. 27, 1923 from which the present application is a division. After the rods are all in position, the free 70 ends of the sheets may be easily gripped by the tongs and the separation of the sheets may be completed.

It will be apparent that the present mechanism is adaptable for use not only with so-called "stickers" but if desired with all of 75 the sheets to be separated.

Due to the even pull exerted on the sheets and the smoothing influence of the loosely mounted or journaled rods 12, wrinkling and tearing of the sheets is prevented, and 80 the separation thereof is accomplished easily and quickly.

I claim:

1. Opening mechanism for a pack of 85 sheets including a plurality of loosely mounted separating bars free to move with the movement of the sheets, and means for drawing the sheets of the pack over opposite sides of adjacent bars.

2. Opening mechanism for a pack of 90 sheets, comprising means adapted to loosely engage between adjacent sheets, and means for producing relative movement between the stripping means and the pack to cause the stripping means to separate the sheets.

3. Opening mechanism for a pack of 95 sheets, comprising a plurality of loosely mounted separating bars free to move with the movement of the sheets, standards loosely supporting said bars, and means for drawing the sheets of the pack between said stand- 100 105

ards and over the opposite sides of adjacent bars.

4. Opening mechanism for a pack of sheets including a loosely positioned separating bar free to move with the movement of the sheets, and means for drawing one sheet of the pack over each side of the bar.
5. Opening mechanism for a pack of

sheets including a floating bar free to move with the movement of the sheets, and means ¹⁰ for drawing one sheet of the pack over each side of the bar.

In testimony whereof I have hereunto set my hand.

FLORENCE C. BIGGERT, JR.
